Attorneys.

UNITED STATES PATENT OFFICE.

TRUMAN G. PADDACK, OF WYOMING, OHIO, ASSIGNOR TO THE STEARNS AND FOSTER COMPANY, OF LOCKLAND, OHIO, A CORPORATION OF OHIO.

UPHOLSTERY-FOLD.

1,339,281.

Specification of Letters Patent.

Patented May 4, 1920.

Application filed January 26, 1920. Serial No. 353,981.

To all whom it may concern:

Be it known that I, TRUMAN G. PADDACK, a citizen of the United States, and a resident of Wyoming, Hamilton county, Ohio, 5 have invented certain new and useful Improvements in Upholstery-Folds, of which the following is a full, clear, and exact description, reference being had to the drawings forming a part of this specification.

10 My invention relates to folds made in cotton batting to serve as stuffing for upholstery.

The ordinary folds, as employed at the present time, in forming up elongated pads 15 for inserting between seamed pockets of upholstery covers, are not satisfactory from a number of points of view. These folds comprise essentially an original piece of thick cotton batting, which is folded over 20 on itself equally from each side making three thicknesses and a long piece of fairly uniform thickness.

This fold is hard to make in automatic machinery because of the exposed edges, 25 and the difficulty of feeding the thick original piece, and furthermore tends to unfold, when complete or during insertion into the upholstery covers.

Then again, it is not desirable that the 30 edges of an upholstery insert be as thick as the center, since this renders its insertion difficult in the covers and results in the forcing of the batting into an unnatural shape, at the constricted spaces near the 35 seams of the pockets.

A further great defect is that it is a usual occurrence to have the outer one of the three folds, buckle inwardly at the line of fold, thereby resulting in a lop-sided insert, which must ordinarily be refolded before use.

According to my invention, a fairly thin piece of batting is folded, progressively inwardly from the sides, in such a way as to 45 form an insert or fold, which has a heavy core, and a light edge. Such a fold is easily made in automatic machinery and does not have any great tendency to spread. Furthermore there is no tendency of the edges 50 to buckle inwardly, and the fold so formed is easily inserted in upholstery pockets, so as to make a neat and attractive appearance. I accomplish my new fold by that

certain construction and arrangement of parts to be hereinafter more specifically 55 pointed out and claimed.

In the drawings—

Figure 1 is a cross section of the piece of batting before being folded.

Fig. 2 is a cross section showing the 60 initial fold.

Fig. 3 is a like view of an additional initial fold which may be made or omitted, dependent upon the original thickness and width of the unfolded piece. 65

Fig. 4 is a cross section showing the second fold, bringing the initial folds together at the center of the piece.

Fig. 5 is a cross section of the final fold, bringing the remaining edges of the piece 70 over the central core.

Fig. 6 is a sectional perspective showing the fold in place in an upholstery cover.

The piece 1, is a piece of batting, usually 75 of cotton, although some other stuffing material of similar nature, would not amount to a departure from my invention. It is passed longitudinally between folding devices, which turn up and roll down the various folds, to be described below.

I have not shown any machinery in my drawings, since the essentials of my fold would apply, as well to direct hand work although for machinery it has the advantage of easy automatic manipulation. 85

The initial fold 2, is made along the marginal edge of the continuous piece, and may be doubled over as at 3, when it is desired to employ a very wide, and quite thin piece of batting to begin with. 90

Having formed the initial fold, the two folded edges are brought in to the center of the piece (Fig. 4) and laid on top of each other, thereby forming a core lengthwise of the piece.

The final fold brings up the double thickness flaps 4, 4, and laps them over the top of the piece (Fig. 5) thereby covering over the core, and leaving the edges of the completed fold, of much less thickness than the 100 core thereof.

As heretofore stated, this fold or upholstery insert will keep its shape, due to the fact that the outside flaps are bent up over a central core and are of double width. 105 The cross section of the piece is in the

shape of an arch, and therefore is adapted for an insert between covers 5, 6, of a piece of upholstery covering, to lie neatly between the seams 7, 7, that form the batting 5 receiving pockets thereof. As shown in Fig. 6 the fold when inserted between covers is compressed so as to obliterate all lines of cleavage.

There are no edges of cotton to catch in 10 the fingers, and no curved or buckled edges to distort the piece.

It is my desire that the doctrine of equivalents be applied in the construction of my claims that follow.

15 Having thus described my invention, what I claim as new and desire to secure by Letters Patent, is:—

1. An upholstery fold for cotton and the like comprising a strip of such material, 20 having initial narrow marginal folds

brought together centrally of the strip to form a core lengthwise of the fold.

2. An upholstery fold for cotton and the like comprising a strip of such material, having marginal folds initially formed 25 along the edges thereof and then brought together and lapped along the center of the material, with the remaining material brought up and over the top of the core formed by said folds.

3. An upholstery insert of cotton or the like comprising a piece of such material, having the original edges thereof formed into a plurality of thicknesses, and said thickened edges brought to the center of 35 the piece and lapped to form a core lengthwise of the insert, said core not being of the full width of the completed insert.

TRUMAN G. PADDACK.
